VARIABLE PITCH PROPELLER

William J. Fike, Pavilion, Wyo.

Application February 6, 1941, Serial No. 377,756

5 Claims. (Cl. 170—163)

This invention relates to a novel variable pitch propeller for aeroplanes and more particularly to a propeller having a hollow hub portion in which a pair of propeller blades are journaled and having gear means connecting the inner ends of the blades to a member disposed within the hub and adapted to be actuated by the movement of centrifugal weights for increasing the pitch of the blades as the speed of rotation of the hub member increases.

Still another aim of the invention is to provide spring means adapted to operate in conjunction with the pressure of air on the propeller blades for reducing the pitch of the blades when the speed of rotation of the propeller is diminished sufficiently so that the force exerted by the spring means and the pressure of air on the propeller blades is sufficient to overcome the force exerted by the centrifugally operated weights.

Still a further aim of the invention is to provide manually operative means capable of being operated from the cabin of an aeroplane equipped with the propeller for manually increasing or reducing the pitch of the propeller blades to vary the pitch of the blades to obtain the maximum efficiency under different flying conditions such as taking off, climbing and cruising.

Still a further aim of the invention is to provide a variable and constant speed propeller of very simple design and construction which may be manufactured and sold at a much lower price than devices for the same purpose now on the market, which can be easily operated and controlled, and which may be readily applied to replace a conventional propeller and which will require very few changes in the engine to adapt it for use with the variable pitch propeller.

Still another aim of the invention is to provide a construction of variable pitch propeller which can be controlled manually or automatically.

Other objects and advantages of the invention will hereinafter become more fully apparent from the following description of the drawings, which illustrate a preferred embodiment thereof, and wherein:

Figure 1 is a transverse central sectional view, partly in elevation, of the variable pitch propeller.

Figure 2 is a vertical sectional view taken substantially along the plane of the line 2—2 of Figure 1.

Figure 3 is a transverse central sectional view taken substantially along the plane of the line 55

3—3 of Figure 2, and at right angles to Figure 1.

Figure 4 is a front elevational view of the same with the detachable forward section of the hub housing removed, and

5 Figure 5 is a sectional view taken substantially along the plane of the line 5—5 of Figure 1.

10 Referring more particularly to the drawings, wherein like reference characters designate like or corresponding parts throughout the different views, 10 designates a portion of the forward end of the cowling of an aeroplane from which projects a crankshaft 11.

15 The variable pitch propeller, designated generally 12, and comprising the invention, includes a hub, designated generally 13, having a centrally disposed sleeve portion 14 for engaging the crankshaft 11 and which is adapted to be keyed thereto in any conventional manner, not shown.

20 The crankshaft 11 is provided with a restricted threaded outer end 15 for receiving a nut 16 which engages the outer end of the sleeve member 14 for retaining it in position on the crankshaft 11. The sleeve member 14, adjacent its rear end, is provided with an integral outwardly projecting housing section 17 which is provided with a forwardly curved outer portion which terminates in an outwardly projecting flange 18. A removable housing section 19 is provided with a central opening 20 for engaging a restricted portion 21 in the forward end of the sleeve member 14.

25 The housing section 19 is curved rearwardly and toward the housing section 17 and is provided with a flange 22 at its outer end which abuts against the flange 18 and which is attached thereto by means of nut and bolt fastenings 23 which extend through aligned openings 24 in the flanges 18 and 22. The shape of the hub housing is clearly illustrated in Figure 2.

30 The housing sections 17 and 19 are provided with diametrically opposed outwardly bowed semi-circular portions 25, as seen in Figures 1, 2 and 4, having inwardly opening circumferentially disposed grooves 26 for receiving anti-friction bearing means 27.

35 A pair of corresponding socket members 28 are journaled in the bores 29 of the hub housing formed by the complementary portions 25, and are provided with flanges 30 at their inner ends

40 and with inwardly tapered bores 31 which extend longitudinally therethrough and which are preferably polygonal shaped in cross section. A pair of propeller blades 32, portions only of which are illustrated, are provided with tapered 45 polygonal shaped shank ends 33 sized and shaped

to fit snugly in the bores 31 for keying the blades 32 to the socket members 28. The shank ends 33 are provided with restricted threaded stems 34 at their inner ends for receiving nuts 35 which engage the inner ends of the socket members 28 to retain the blades 32 in engagement therewith. The socket members 28 are provided with beveled gear segment portions 36 which are formed integral with their flanges 30 and which are disposed in the hollow interior of the hub. The gear segments 36 each extend through an arc of approximately 90 degrees or one-quarter of a circle.

The sleeve member 14, as best seen in Figure 3, is provided with substantially straight outwardly opening grooves 37 which are disposed in diametrically opposed relationship and transversely of its circumference. A ring 38 is turnably mounted on the portion of the sleeve member 14 which is provided with the grooves 37 and is provided with slots 39 which are disposed at angles of approximately 30 degrees to the grooves 37. A collar 40 is loosely mounted on the ring 38 and is provided with diametrically opposed threaded openings 41 for receiving the threaded shank portions of studs 42 which are provided with restricted shank ends 43 which extend through the slots 39 and into the grooves 37 which are complementary thereto. It will thus be apparent that the collar 40 is prevented from rotating relatively to the sleeve member 14 but can slide relatively thereto and a sliding motion of the collar 40 will cause the studs 42 to slide relatively to the slots 39 for imparting a rotating motion to the ring 38. Ring 38 is provided with diametrically opposed beveled gear segments 44 at its inner end which are substantially the same length as the gear segments 36 and which are arranged to mesh therewith, as best seen in Figures 1 and 5 so that a turning movement of the ring 38 will cause the sockets 28 and the propeller blades 32 to revolve relatively to the hub 13 to vary the pitch of the propeller blades 32.

Referring particularly to Figures 1 and 4, sleeve member 14, adjacent its outer end, is provided with diametrically opposed flat portions 45 forming continuations of the restricted portion 21 and which are adapted to receive the intermediate portions of bars 46 which are secured thereto by means of nut and bolt fastenings 47 which extend through openings 48 on opposite sides of the shaft 11 and through aligned openings in the bars 46, seen in dotted lines at 49. Nut and bolt fastenings 50 extend through aligned openings adjacent the ends of the bars 46 for engaging the sleeves 51 which are turnably mounted thereon between the complementary ends of the bars 46 and which are formed integral with the apexes of the angular arms 52. The arms 52 are provided with short ends 53 which extend inwardly of one another and the longer ends 54 which are normally disposed in substantially parallel relationship to one another and to the sleeve member 14 and which are provided with weights 55 at their free ends and intermediate of the front and rear of the hub housing and in the enlarged diametrically opposed recessed portions 56 thereof of which portions are substantially at right angles to the bore portions 29.

Referring particularly to Figures 1 and 4, the nut and bolt fastenings 47, at opposite ends thereof, carry clips 57 having eyelets in each of which is connected an end of a contractile

coil spring 58. The opposite ends of the contractile coil springs 58 are connected to apertured enlargements 59 on the forward end of the collar 40. The collar 40 is provided with 5 diametrically opposed extensions 60 at its forward end which extend into the spaces between the complementary ends of the bars 46 and which bear against the rear edges of the ends 53.

Rods 61 extend through and are loosely disposed in openings 62 in the housing portion 17 and are provided with forward, inner threaded ends which engage threaded sockets 63 in the rear end of the collar 40. The opposite, outer ends of the rods 61 are secured to a thrust collar 64 which is disposed on the outer side of the housing portion 17 and around the crank-shaft 11 and which is provided with an annular inwardly opening groove 65.

Referring particularly to Figures 1 and 3, a 20 shaft 66 is journaled in bearings 67 connected to the forward end of the cowling 10, such shaft being disposed below the crankshaft 11 and being provided with spaced crank arms 68 which are keyed thereto and which are provided with outwardly curved free ends 69 for loosely engaging the groove 65. A crank arm 70 is keyed to one end of the shaft 66 and has a rod 71 pivotally connected to its opposite, free end. The rod 71 telescopes into a tube 72 and is provided with 25 a pin 73 which extends transversely therethrough and the ends of which project therefrom for slidably engaging diametrically opposed longitudinal slots 74 in the tube 72. The tube 72 is adapted to extend into the cabin of the aeroplane and to be connected to suitable means, not shown, such as a lever by means of which a reciprocating motion can be imparted to the parts 71 and 72 for actuating the shaft 66 and the crank arms 68 for moving the thrust collar 64 toward and away from the hub 13 to move the collar 40 forwardly and rearwardly of the ring 38.

If the engine of the aeroplane, not shown, is operating at a constant throttle opening the speed of rotation of the propeller 12 will vary depending upon the pitch of the blades 32 and will increase as the pitch of the blades is decreased or decrease when the pitch of the blades is increased. For maximum efficiency, the pitch 30 of the blades should be slight when the aeroplane is taking off in ascending as the load on the engine is greater under such conditions and it is therefore preferable to have the engine turning over as fast as possible. In cruising, where the load on the engine is greatly reduced for greater efficiency the pitch of the propeller blades should be increased so that the maximum amount of pull may be exerted thereby.

The rearward movement of the collar 40 causes the ring 38 to turn in a direction for increasing the pitch of the propeller blades 32 and the forward movement of the collar 40 therefore causes the ring 38 to turn in an opposite direction for decreasing the pitch of the blades 32. In the drawings, the collar 40 is shown in its forwardmost position and the blades 32 are therefore set at their minimum pitch. This is the position that the parts will assume when the shaft 11 is not rotating. When the shaft 11 is revolved, the weights 55 will be swung outwardly by centrifugal force to cause the ends 53 of the arms 52 to swing rearwardly and due to the fact that the portions 60 of the collar 40 are in engagement with the rear side or edges of the ends 53 the collar 40 will be moved rearwardly

to actuate the parts, as previously described, to increase the pitch of the propeller blades proportionately with the increase in the speed of rotation of the shaft 11. However, the propeller blades offer greater wind resistance as their pitch is increased and the air impinging upon the propeller blades therefore has a tendency to reduce their pitch which tendency must be overcome by the centrifugal force exerted by the weights 55. Also, the contractile coil springs 58 tend to draw the collar 40 forwardly and against the action of the weights 55 for reducing the pitch of the blades 32 and the pressure of the springs 58 will coact with the energy produced by the air impinging upon the propeller blades to reduce the pitch when the speed of rotation of the shaft 11 is reduced so that the action of the centrifugal weights 55 will be offset by the springs 58 and the air on the blades 32 and conversely to maintain the blades 32 at a correct pitch for the most efficient operation, assuming that the weight and size of the weights 55 and the tension and force of the springs 58 are correctly proportioned. It will thus be seen that under normal flying conditions the blades 32 will be automatically maintained at a proper pitch for the most efficient operation of the aeroplane.

However, for taking off and ascending it is necessary to manually reduce the pitch of the blades 32 and this is accomplished by the link 71, 72 being moved rearwardly to the full extent of its movement so that the pin 73 will engage the outer ends of the slots 74 to draw the rod 71 rearwardly to rock the shaft 66 to move the thrust collar 64 to its forwardmost position in which position the parts are held by the link 71, 72 against the action of the weights 55. Similarly, the blades 32 can be held at a high pitch by moving the linkage connection 71, 72 to an extreme forward position for holding the thrust collar 64 in a rearmost position. When the linkage connection 71, 72 is in an intermediate position the connection 73, 74 thereof will permit the collar 64 to move forwardly and rearwardly so that the adjustment of the pitch of the propeller blades 32 can be varied automatically, as previously explained, by the weights 55 and the springs 58.

If desired, the rod 71 can be secured fast to the tube 72 in which case the propeller 12 can be controlled manually and when so controlled the springs 58 may be omitted and the centrifugal weights 55 employed to counteract the pressure of the air impinging upon the blades 32 so that very little energy will be required to vary the pitch of the blades 32.

Various modifications and changes are contemplated and may obviously be resorted to as only a preferred embodiment of the invention has been disclosed.

I claim as my invention:

1. A variable pitch propeller for aeroplanes comprising a hollow hub member keyed to a crankshaft, propeller blades, said hub member having sockets for receiving and journaling the adjacent ends of said propeller blades, said hub member having a hollow portion, weights having arms pivotally connected to the hub and disposed therein and arranged to be swung outwardly by centrifugal force, a collar mounted to slide longitudinally of the hub and having portions for engaging said arms and to be actuated by the outward movement of the weights, a ring rotatably mounted in the hub, means for connecting said ring and collar whereby the sliding

movement of the collar will cause said ring to be turned, said ring being provided with circumferentially spaced gear segments, said propeller blades being provided with gear segments for meshing with the gear segments of the ring whereby the propeller blades will be turned on their longitudinal axes relatively to the hub by the turning movement of the ring for varying the pitch of the propeller blades, rods slidably mounted in the inner end of said hub, said rods having corresponding ends connected to said collar and opposite ends projecting from the hub, a thrust collar secured to the last mentioned ends of said rods, and manually operable means for engaging and moving the thrust collar in one direction for turning said ring in one direction.

2. A variable pitch propeller comprising a hollow hub member having a centrally disposed sleeve portion keyed to a driven shaft, propeller blades having their inner ends journaled in the hub member, said sleeve portion having substantially straight transversely disposed outwardly opening grooves, a ring turnably mounted on the grooved portion of the sleeve member and provided with slots disposed at an angle to said grooves, a collar loosely mounted on said ring and provided with studs extending through said slots and into said grooves, said ring being provided with circumferentially spaced gear segments, said blades being provided with gear segments for meshing with the gear segments of the ring, manually operative means connected to said collar for sliding it relatively to the sleeve member for rotating the ring to turn the blades on their longitudinal axes for varying the pitch of the blades, arms pivotally mounted in the hub member and having free ends provided with weights adapted to be swung outwardly by the centrifugal force caused by the rotation of the hub member, and said arms being provided with angularly disposed extensions for engaging said collar for moving it in one direction relatively to the ring for turning the ring in a direction for increasing the pitch of the propeller blades.

3. A variable pitch propeller comprising a hollow hub member having a centrally disposed sleeve portion keyed to a driven shaft, propeller blades having their inner ends journaled in the hub member, said sleeve portion having substantially straight transversely disposed outwardly opening grooves, a ring turnably mounted on the grooved portion of the sleeve member and provided with slots disposed at an angle to said grooves, a collar loosely mounted on said ring and provided with studs extending through said slots and into said grooves, said ring being provided with circumferentially spaced gear segments, said blades being provided with gear segments for meshing with the gear segments of the ring, manually operative means connected to said collar for sliding it relatively to the sleeve member for rotating the ring to turn the blades on their longitudinal axes for varying the pitch of the blades, said manually operative means comprising rods connected to said collar and extending through and slidably mounted in the inner side of the hub member, a thrust collar secured to the rods and disposed on the outer side of the hub member and provided with an annular inwardly opening groove, and link members loosely engaging the groove in the thrust collar and adapted to be manually actuated for moving the thrust collar toward and away from

the hub member for actuating the first mentioned collar.

4. A variable pitch propeller comprising a hollow hub member having a centrally disposed sleeve portion keyed to a driven shaft, propeller blades having their inner ends journaled in the hub member, said sleeve portion having substantially straight transversely disposed outwardly opening grooves, a ring turnably mounted on the grooved portion of the sleeve member and provided with slots disposed at an angle to said grooves, a collar loosely mounted on said ring and provided with studs extending through said slots and into said grooves, said ring being provided with circumferentially spaced gear segments, said blades being provided with gear segments for meshing with the gear segments of the ring, manually operative means connected to said collar for sliding it relatively to the sleeve member for rotating the ring to turn the blades on their longitudinal axes for varying the pitch of the blades, spring means connected to said collar for urging it in a direction for turning the ring in a direction to reduce the pitch of the propeller blades.

5. A variable pitch propeller comprising a hol-

low hub member having a centrally disposed sleeve portion keyed to a driven shaft, propeller blades having their inner ends journaled in the hub member, said sleeve portion having substantially straight transversely disposed outwardly opening grooves, a ring turnably mounted on the grooved portion of the sleeve member and provided with slots disposed at an angle to said grooves, a collar loosely mounted on said ring and provided with studs extending through said slots and into said grooves, said ring being provided with circumferentially spaced gear segments, said blades being provided with gear segments for meshing with the gear segments of the ring, manually operative means connected to said collar for sliding it relatively to the sleeve member for rotating the ring to turn the blades on their longitudinal axes for varying the pitch of the blades, centrifugally actuated weights for engaging the collar to urge it in one direction for turning the ring in a direction to increase the pitch of the propeller blades, and spring means for urging the collar in the opposite direction.

25

WILLIAM J. FIKE.
